INVENTOR.
Stephen Hermanowich,
BY

Geo. P. Kimmel. ATTORNEY.

UNITED STATES PATENT OFFICE.

STEPHEN HERMANOWICH, OF ELLWOOD CITY, PENNSYLVANIA.

ICE-CARD HOLDER.

Application filed November 4, 1925. Serial No. 66,788.

To all whom it may concern:

Be it known that I, STEPHEN HERMANOWICH, a citizen of the United States, residing at Ellwood City, in the county of Lawrence and State of Pennsylvania, have invented certain new and useful Improvements in Ice-Card Holders, of which the following is a specification.

This invention relates to indicators, and 10 has for its object to provide, in a manner as hereinafter set forth, a device of the class referred to having means for indicating to a tradesman the desired quantity of merchandise, such as ice, which is to be delivered at the residence with which the indicator is employed.

Further objects of the invention are to provide, in a manner as hereinafter set forth, an indicator having the indicating 20 element thereof provided with means for designating, by weight, the amount of ice to be delivered to the occupant of a dwelling and furthermore with means whereby the indicator element is detachably secured 25 in position, when set, to indicate the amount of ice desired.

Further objects of the invention are to provide, in a manner as hereinafter set forth, an indicator which is simple in its 30 construction and arrangement, strong, durable, compact, thoroughly efficient in its use, conveniently adjusted, and inexpensive to manufacture.

With the foregoing and other objects in 35 view the invention consists of the novel construction, combination and arrangement of parts, as hereinafter more specifically described, and illustrated in the accompanying drawings, wherein is shown an embodiment 40 of the invention, but it is to be understood that changes, variations and modifications can be resorted to which fall within the scope of the claim hereunto appended.

In the drawings wherein like reference characters denote corresponding parts throughout the several views:—

Figure 1 is a front elevation of an indicator, in accordance with this invention, and illustrating the indicator element in set position.

Figure 2 is a view similar to Figure 1 with the concealing member removed, and taken on section line 2—2 Figure 3.

Figure 3 is a longitudinal sectional view 55 of the indicator.

Figure 4 is a section on line 4—4 Figure 3.

Referring to the drawings in detail 1 generally indicates a hanger member consisting of a pair of oppositely disposed arms 2, 3, 60 each formed with an inturned forward portion 4 terminating in a sleeve 5 disposed in the plane of the longitudinal median of the hanger 1. The arms 2 and 3 are connected together, intermediate their ends, by a cross 65 bar 6, arranged rearwardly with respect to the sleeve 5 and formed centrally with a polygonal shaped opening 7, and further having projecting from the rear thereof a hollow offset portion 8, formed with a centrally disposed opening 9 arranged in alignment with the polygonal shaped opening 7 and of a diameter less than the width of the latter.

Positioned forwardly and rearwardly 75 with respect to the sleeve 5 is a combined longitudinally disposed supporting, bearing and clamping element and which consists of a substantially elongated cylindrical stem 10 terminating at its outer end in a polygonal shaped disk 11, with which is formed integral a circular head 12 of a diameter materially greater than the width of the disk 11 whereby the head 12 will project from the disk. The rear end of the stem 80 10 terminates in a reduced polygonal shaped extension 13, from which extends rearwardly a peripherally threaded cylindrical bar 14 of materially less diameter than the diameter of the stem 10. The polygonal extension 13 is seated in the opening 7 and prevents rotative movement of the stem 10. The rod 14 projects through the offset 8 and also through the opening 9 and carries a clamping nut 15 which coacts with the disk 85 11 and head 12 for a purpose to be presently referred to.

Mounted on the stem 10 and interposed 90 between the disk 11 and bar 6, and as well extending through the sleeve 5, is a revolvable member 16 having a polygonal shaped forward end terminal portion 17 and a reduced intermediate portion 18 which provides a shoulder 19 abutting against the forward end of the sleeve 5. The member 100 16 further includes a reduced rear terminal portion 20 which abuts the bar 6 and carries a flange collar 21 having the flange 22 thereof, toothed or knurled as at 23. The collar 21 is suitably connected to the member 16 105 110

and is employed for revolving it. The toothed or knurled flange 22 provides a grip for the operator when revolving the member 16.

- 5   Mounted on the polygonal shaped forward terminal 17, of the member 16, so as to bodily rotate therewith, is an indicator element 24, in the form of a circular disk, provided with indicia at spaced points, as at 25 to 10 indicate the amount of ice desired and further provided with indicia as at 26 to indicate if no ice is desired. Associated with the indicator element 24, for the purpose of concealing the indicia other than that desired to be visible, is a concealing member 27, of the same diameter as the diameter of the indicator element 24, and which is provided with a cut-out portion 28 for the purpose of exposing any one of the indications 15 provided by the indicia 25 and 26. The concealing member 27 is mounted on the polygonal shaped disk 11 and is stationary. The cut-out portion 28 is arranged at the top of the indicator element 24.
- 20   The arm 2, as well as the arm 3, of the hanger 1, is formed with an outwardly extending flange 29, through which extends a holdfast device 30, for fixedly securing the hanger to a support 31, which may be a door, door-frame or window-frame or one of the 25 walls of a dwelling.
- 25   The nut 15, in connection with the disk 11 and head 12, when adjusted on the rod 14 will clamp the member 16, as well as the indicator element 24, after the indicator element has been positioned to expose the desired indicia. The shoulder 19, in connection with the forward end of the sleeve 5 also assists in clamping the indicator element 30 in position. When the nut 15 is shifted

ed rearwardly on the rod 14, the member 16 can be revolved for the purpose of positioning the indicator element 24 to expose the desired indicia.

It is thought that the many advantages 45 of an indicator, in accordance with this invention, and for the purpose set forth, can be readily understood, and although the preferred embodiment of the invention is as illustrated and described, yet it is to be understood that changes in the detail of construction can be had which will fall within the scope of the invention as claimed.

What I claim is:—

An indicator comprising a hanger element formed with a lengthwise extending sleeve at the outer end thereof, a revoluble member extending through and of greater length than said sleeve and projecting forwardly and rearwardly of the latter and 50 further abutting against the outer end of the sleeve, a combined supporting, bearing and clamping element extending through and of greater length than the length of said member, an indicator element mounted on 55 the forward end of said member and bodily carried therewith, a stationary concealing member carried by said combined supporting, bearing and clamping element, and said latter element including means for detachably clamping said revoluble member stationary to maintain the indicator element in set position, said means coacting with the forward end of said sleeve, and said concealing member having a cut-out portion to 60 expose an indication on said indicator element.

In testimony whereof, I affix my signature hereto.

STEPHEN HERMANOWICH
